UNITED STATES PATENT OFFICE.

FREDERICK T. KITCHEN, OF NEW YORK, N. Y., ASSIGNOR TO GOLD CAR HEATING & LIGHTING COMPANY, OF NEW YORK, N. Y., A CORPORATION OF NEW YORK.

ELECTRIC HEATER.

1,147,951.

Specification of Letters Patent.

Patented July 27, 1915.

Application filed August 8, 1914. Serial No. 353,891.

To all whom it may concern:

Be it known that I, FREDERICK T. KITCHEN, a citizen of the United States, residing in Staten Island, in the borough of Richmond, 5 city and State of New York, have invented certain new and useful Improvements in Electric Heaters, of which the following is a specification.

My invention relates to electric heaters 10 and is particularly adapted to that type of such apparatus as is employed for the heating of passenger cars.

The invention has for its object to provide an improved construction of heater 15 whereby a heating unit may be readily removed through the front of the casing by a simple removal of the front plate or screen and if a plurality of heating units are employed any one of them may be similarly 20 removed and without disturbing the other heating units within the heater casing, and in either case without the removal of the end plates, and further to attain this object in a quick and economical way, having few 25 parts to get out of order or to become displaced from the rough usage ordinarily given such apparatus.

My invention consists in the provision of means for supporting the said heating unit 30 or units within the casing, whereby one or more of them may be removed through the front of the casing upon the removal of the cover.

A desirable form in which my invention 35 may be employed is illustrated in the accompanying drawings, wherein:

Figure 1 is a longitudinal section of one side of a trolley car illustrating the riser under the seat, and the covers or shields 40 which protect the front of the heaters and permit the heat to circulate therethrough; Figs. 2, 3 and 4 are cross-sections of a heater embodying my invention, taken on corresponding lines in Fig. 5; Fig. 5 is a face 45 view, partly in section, of the said improved heater partly broken and taken on the line 5—5 of Fig. 2, so as to remove the cover plate; Fig. 6 is a longitudinal section on the line 6—6 of Fig. 2, partly broken away; 50 Figs. 7 and 8 are longitudinal sections, partly broken away, illustrating another form of end block and different modes of connecting the wires; Fig. 9 is a cross-section on the line 9—9 of Fig. 7; and Fig. 10

is an end view illustrating the location of 55 the insulating plugs in the end plate.

My invention is illustrated as applied to that type of heater wherein a casing A is inserted behind the riser B of the car-seat, and has a front plate or cover C which has 60 openings to permit the escape of heat from the heater to the car, and which is made removable by removing the screws c. It is frequently advisable to divide the heater contained in such casing into small units 65 rather than to have a large one for the purpose of both controlling the supply of heat so as to increase or diminish the same at will, and also to reduce the chances of the heater getting out of order and so depriving 70 the railroad of the car while the heater is being repaired.

It is highly desirable where a plurality of heating units are employed within each 75 casing that each heating unit should be capable of being removed separately and without interfering with or preventing the continued use of the other unit or units within the casing. My invention provides a desirable way of accomplishing this result and 80 not only permits of the removal of all or any of the heating units separately and without interfering with the other heating unit or units, but also permits such removal without removing any other part of the 85 casing than such part as is easily accessible and removable, to wit, the cover or front plate or screen.

In the accompanying drawings the heaters are illustrated as being mounted upon supports D which, as constructed by me in the form illustrated, take the form of plates which are suitably secured to the casing at the rear thereof and extend substantially half-way toward the front or cover of the 95 casing. Each of the plates is provided with means for supporting one of the heating units separately, and such means are illustrated as taking the form of slots d into which one of the heaters is inserted. 100

Heating units E, as illustrated, each comprise a core e which is spirally corrugated and receives a helically wound wire e¹ which is the resistance element of the heater. These cores e are provided with end-blocks 105 F and contain a central metal rod f which passes through the core and through perforations in the end blocks F and is held in

place by suitable means as by being threaded and having thereon nuts f^1 . The said rod fills the double function of holding the heating unit and its end-blocks together and of providing a return wire when desired.

The said heating units E are supported within the slots d of the supporting plates D as by means of small slots or channels f^2 formed therein and which receive the plate D .

10 It is advisable to employ means for the purpose of holding the heating units E in position in the supports D , and various means may be employed for this purpose.

15 As shown in Fig. 2 I employ a threaded rod G which is suitably supported, as for instance, upon the plate D and which at its outer end carries a bracket that engages both of the heating units illustrated and 20 holds them in place. In Fig. 2 the means is illustrated as a disk or washer g which is held in position by a lock nut g^1 and is therefore removable as desired.

My invention is not concerned with the 25 particular construction of end-block employed. In Fig. 2 I have illustrated a simple form of end-block which may be employed and is well adapted for service when the return wire is connected to the rod f 30 after passing through the perforation f^3 in the said end-block. On the right hand side of Fig. 5 is illustrated a desirable form of end-block which however forms no part of my invention, but is the subject of a separate application filed by A. O. Bailey on 35 August 6, 1914, Serial No. 855,351, and is simply illustrated because it is well adapted for use with my invention. The said end-block, as illustrated in Figs. 3, 4 and 5 is 40 designated H . A leading-in wire h passes through a perforation in an insulator a^2 in an end wall of the casing and is connected to a clip h^1 and the heating wire e^1 passes through a perforation h^2 in the end block 45 and is connected to the clip h^1 . The return current passes through the central rod f and is wired to a similar clip h^3 , to which is also connected the main return wire h^4 . This form of end-block is illustrated as 50 mounted within the plates D which are similar to those of Fig. 2, but the end-block is not slotted. Accordingly the bracket g^2 of Fig. 4, by which the said blocks are held in place, has a pendant flange g^3 which embraces the sides of both blocks and holds 55 them in place and permits their independent removal by the removal of the end bracket by unscrewing of the lock nut g^1 . It may be desirable to have the said electric heaters 60 connected in series rather than in multiple, and in such case the rod f will simply perform the function of holding the parts of a heater unit together. Constructions containing my improvement and having this 65 arrangement are illustrated in Figs. 7 and

8. In Fig. 7 the leading-in wire is illustrated as connected to a clip I , to which the heating wire is also connected, and such clip is repeated at each end of the core. The same arrangement of electric wires may, 70 however, be provided without the clip, as illustrated in Fig. 8, where the clips are omitted and a simple connection between the leading-in wire and the heating wire is provided. The clip I as in Fig. 7 is secured 75 to a clamp i which is held upon the core by a screw i^2 .

The casing is provided with the usual semicylindrical shell α having end-walls α' , and these are provided with porcelain or similar insulating plugs α^2 through which may pass the electric wires. In case the central rod f is employed as part of the return wire, such insulating plugs α^2 need be provided at but one end of the casing as 80 illustrated in Figs. 5 and 6; but in case the heaters are arranged in series they should be at both ends as in Figs. 7 and 8, wherein are illustrated a plurality of such plugs at 85 each end for employment with a plurality of 90 heaters.

I have illustrated my invention as adapted for the use of two heating units in a casing; but my invention is not concerned with the number of heating units supported. It may 95 be employed for a greater number than two, and its construction is such that it is well adapted for the support of a single heating unit in a casing. In constructions where a plurality of heating units are supported, it 100 is desirable for purposes of a convenient size of casing, that the slots in the plate D should open toward the movable cover. But it will be obvious that this arrangement is not so important in case a single heating 105 unit is employed, in which case the plate D , as shown in Fig. 2, could be divided on substantially the line 6—6 in said figure, as but one-half of the plate would be required for the support of a single heater, and this plate could be shifted a quarter turn so that its 110 slot would open toward the top of the casing. It is, however, important that the opening to the slot should be accessible 115 through the front of the casing so that the heater could be inserted therein upon removal of the cover. The junction box, end blocks, etc., could be the same as described. Nor is my invention concerned with the particular manner of connecting the electric 120 wires, nor with the particular construction of end block or heater, but it relates solely to the manner of supporting the heater unit or units so as to permit their removal through a side opening of the casing, as described, and without disturbing the other heaters, if more than one heater is employed, and without removing the ends of 125 the casing.

The invention is illustrated in connection 130

with a car having seats running longitudinally, but, of course, the type of car is unessential, and the invention is equally useful in connection with any of the standard 5 types of cars.

My invention is not concerned with the particular construction of casing, nor heater unit employed, and other constructions than those illustrated may be used in connection 10 therewith. Nor is my invention limited to the particular number of units illustrated, nor to their exact construction as these may be changed and equivalent devices may be employed within the limits of the appended 15 claims.

I claim:

1. In an electric heater having a casing and a removable front plate, and means for independently supporting a plurality of 20 heaters within said casing, said supporting means permitting the removal of each heater therefrom independently and without interfering with the other heaters, a space being provided between said supporting means 25 and the end of the casing forming a junction box whereby upon removal of the front plate the electrical connections are accessible and each heater may be separately removed through the front of the casing.

2. In an electric heater having a casing and a removable front plate, means for independently supporting a plurality of heaters within said casing, said supporting means permitting the removal of each heater therefrom independently of and without interfering with the other heaters, a space being provided between said supporting means and an end of the casing forming a junction box, whereby upon removal of the front 40 plate the electrical connections are accessible and each heater may be separately removed through the front of the casing, and removable means for retaining said heaters in said supporting means.

3. In an electric heater having a casing, end plates and a removable front plate, and adapted to contain a plurality of heaters, a supporting plate at each end of said casing for said heaters inside of said end plates, 50 each plate having a separate recess for each heater opening toward the front whereby upon removal of the front plate each heater might be separately removed.

4. In an electric heater having a casing, 55 end plates and a removable front plate, a plurality of heaters therein, each heater having a separate end-block at each end, a supporting plate at each end of said casing for said heaters inside of said end plates, 60 each plate having a separate recess for each heater opening toward the front whereby upon removal of the front plate each heater may be separately removed, and removable means for retaining said heaters in said 65 plates.

5. In an electric heater having a casing and a removable front plate, a plurality of heaters within said casing, individual insulating end-blocks for each end of each of said heaters, a support in said casing for 70 said end-blocks, each of said heaters being adapted to be separately removed from said supports upon removal of the front plate.

6. In an electric heater having a casing and a removable front plate, a plurality of 75 heaters within said casing, individual insulating end-blocks for each end of each of said heaters, a support in said casing for said end-blocks, each of said heaters being adapted to be separately removed from said 80 supports upon removal of the front plate, and removable means for retaining said heaters in said support.

7. In an electric heater adapted to contain a plurality of heaters and permit their 85 separate removal, a casing, end plates, a removable cover, a plate in said casing and between said end plates having a slot for each heater and each slot opening toward the front of the casing, a retainer on said 90 plate adapted to hold said heaters in place in said slots, said retainer being removable to permit the withdrawal of any desired one of said heaters through the front of the casing upon the removal of the cover.

8. In an electric heater adapted to contain a plurality of heaters and permit their separate removal, a casing, a removable cover, a plate therein having a slot for each heater and each slot opening toward the 100 front of the casing, a threaded bolt on said plate, a retaining bracket thereon adapted to hold said heaters in place in said slots, a nut to hold said bracket in place, said retainer being removable to permit the withdrawal of any desired one of said heaters through the front of the casing upon the removal of the cover.

9. In an electric heater having a casing and a plurality of heating units therein, 110 independent end blocks for each heating unit, and means for supporting each of the said end blocks independently of the others, said means being located within the casing and providing a junction box between the 115 said supports and an end of the casing, whereby the electrical connections are accessible, and each heater may be removed without affecting the other heaters, through the front of the casing.

10. In an electric heater having a casing, end walls, a removable front plate and a plurality of heating units therein, a supporting plate for said heaters having a plurality of recesses therein opening toward 125 the front plate, said plate being located within said casing and providing a space between the plate and one of said end walls, forming a junction box.

11. In an electric heater having a casing 130

and a removable front plate, means for independently supporting a plurality of heater units in said casing comprising a plate having a plurality of channels opening toward 5 the front of the casing and an independent end block of insulating material for each heater adapted to be received in one of said channels, said plate located within said casing and a space being provided between it 10 and an end plate forming a junction box, and the removal of the front plate affording access to the electric connections and permitting the independent removal of any of said heater units through the front without interfering with the other heater units.

12. In an electric heater having a casing and a removable cover, a plurality of heating units in said casing, means in said casing for holding each of said heating units 20 therein, said holding means being accessible upon removal of the cover and adapted to permit the separate removal of any heating unit therefrom without disturbing the other heating unit or units, and space being provided within said casing for electrical connections and said electrical connections being accessible upon removal of the cover.

13. In an electric heater having a casing, end walls, a removable front plate and a

heating unit therein, a supporting plate for 30 said heater having a recess therein, the opening to which is accessible from the front of the casing, said plate being located within said casing and providing a space between the plate and one of said end walls, forming 35 a junction box.

14. In an electric heater having a casing and a removable front plate, means for supporting a heater unit in said casing comprising a plate having a channel, the opening to which is accessible from the front of the casing for receiving an end block and an end block of insulating material for said heater adapted to be received in said channel, said plate being located within said casing and a space being provided between it and an end plate forming a junction box, and the removal of the front plate affording access to the electric connections and permitting the removal of said heater through 50 the front.

In witness whereof, I have hereunto signed my name in the presence of two subscribing witnesses.

FREDERICK T. KITCHEN.
